(57) **CLAIM**

The ornamental design for an angle-adjustable water pipe, as shown and described.

DESCRIPTION

FIG. 1 is a perspective view of an angle-adjustable water pipe showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The water pipe is shown broken away in FIGS. 1-5 to indicate indeterminate length.
